TRANSVERSELY SLIDING BREECH BOLT
LOCK FOR AUTOMATIC FIREARMSClarence E. Simpson, Springfield, Mass., assignor
to the United States of America as represented
by the Secretary of War

Application October 29, 1948, Serial No. 57,283

2 Claims. (Cl. 89—187)

(Granted under the act of March 3, 1883, as
amended April 30, 1928; 370 O. G. 757)

1

The invention described in the specification and claims may be manufactured and used by or for the Government for governmental purposes without the payment to me of any royalty thereon.

This invention relates to a gas operated firearm of the automatic type employing a reciprocating bolt having a comparatively short recoil travel.

Numerous prior art firearms of relatively large caliber employ a long bolt travel and frequently use what is known as a U-feed for extracting the cartridge from the firearm belt and seating such cartridge in the chamber of the barrel. For firearms of relatively low rate of fire, in the neighborhood of 600-800 rounds per minute, such a feed is entirely satisfactory because of the relatively long time interval available for the bolt to complete its cycle of feeding and extraction of a cartridge.

It is also common with firearms of this type to employ a breech block or bolt having considerable mass. Obviously to increase the speed of firearms having such a large reciprocating bolt mass, such bolt will have to be moved even faster with the unfortunate result that the reaction forces set up will be so great as to cause considerable breakage of the parts and will therefore require considerable redesign of affected components of the firearm.

In order to obtain a high rate of fire, it is therefore necessary to provide a reciprocating breech member having a very light mass. In addition, a bolt travel of a length not much greater than the length of the cartridge is necessary in order to get the rapidity of fire desired as such shortened bolt travel substantially reduces the time element.

Accordingly it is an object of this invention to provide a firearm having a reciprocating breech member of comparatively light weight wherein a high rate of fire may be obtained.

Another object of this invention is to provide a positive bolt locking device for an automatic firearm wherein locking is accomplished by extreme short movement of the breech lock actuator which is positive in operation and one which will adequately withstand a high breech pressure.

Still another object of this invention is to provide an automatic firearm having a cartridge feeding mechanism operable by the operating slide of the firearm.

Another object of this invention is to provide

2

a latching device for insuring that the firearm bolt will precede the operating slide of the firearm into battery position in properly spaced relationship with respect to the operating member.

5 Still another object of this invention is to provide a cartridge support in the feedway of the firearm to support a cartridge being fed into the chamber while permitting the ejected empty cartridge case to drop through the receiver on the recoil stroke of the firearm.

The specific nature of the invention as well as other objects and advantages thereof will clearly appear from the following description of a preferred embodiment as shown in the accompanying drawings in which:

Fig. 1 is a longitudinal sectional view of the rear portion of the firearm shown with the bolt in the breeched locked battery position.

Fig. 2 is a longitudinal sectional view of the front portion of the firearm with the mechanism in the breeched locked battery position.

Fig. 3 is an enlarged detail fragmentary view showing the position of the cartridge support rods engaging the cartridge in such fashion that the bolt may readily seat the cartridge in the chamber of the firearm.

Fig. 4 is a view similar to Fig. 3 but showing the cartridge support rods in another position to permit ejection of the empty cartridge case.

Fig. 5 is a detail view showing the manner of mounting the extractor in the firearm bolt.

Fig. 6 is a perspective view of the extractor.

Fig. 7 is a view similar to Fig. 1 but showing the bolt in the extreme recoil position with a cartridge in position for feeding into the chamber of a firearm barrel.

Fig. 8 is a view similar to Fig. 2 but showing the mechanism in the extreme recoiled position.

Fig. 9 is a detail view showing the cam slots in the cartridge support rods whereby such rods are rotated to permit feeding of a cartridge or ejection of an empty case.

Fig. 10 is a detail view showing the bolt lock in locked relationship with the bolt and the relationship of the cam in the operating slide with respect to the bearing pins in the bolt lock where such bolt lock is in the locked position.

Fig. 11 is a cross-sectional view taken along the line 11—11 of Fig. 10 showing the bolt lock in locked relationship with the firearm bolt.

Fig. 12 is a top schematic view of the lever arrangement utilized for transversely feeding a belt of cartridges through the feedway of the firearm and also showing the cam slot in the operating slide in the firearm for actuation of such levers.

Fig. 13 is an enlarged detail view showing the elements of the cartridge feeding mechanism in elevation.

Fig. 14 is a top view of the receiver.

Fig. 15 is a longitudinal sectional view of the operating slide.

Fig. 16 is a top view of the operating slide.

Fig. 17 is a left end view of the firearm receiver shown in Fig. 1.

Fig. 18 is a top view showing the locking arrangement for the receiver and receiver extension.

The firearm shown in Fig. 1 comprises essentially a receiver 20, a barrel 30 secured to the forward end of receiver 20 by threads 31, a bolt 40 slidably mounted in receiver 20 and an operating slide 50 slidably mounted in receiver 20 below bolt 40 but connected thereto as will be later described.

Receiver 20 comprises a substantially rectangular block as shown in Fig. 14. A cylindrical boss 21 is integrally provided on the forward end of such receiver and is exteriorly threaded as shown at 22 on which is screwed a barrel jacket 23. Boss 21 is provided with an axial hole 24 and such hole is threaded to receive threaded end 31 of barrel 30. A cover 25 is pivotally mounted on top of receiver 20 by a pin 26. Such cover is releasably secured to receiver 20 by a latch 27 provided at the forward end of cover 25. Opposed integral depending lugs 28 are provided on the underside of cover 25 which support a cartridge belt feed slide 29. A belt feed slide lever 32 is pivotally secured to the underside of cover 25 by a pin portion 33 and functions in a manner as will be later described.

Suitable rectangular ways 34 and 35, as shown in Fig. 17, are provided in receiver 20 and are longitudinally disposed therein to receive respectively operating slide 50 and bolt 40. A receiver extension 36 is secured to the rear end of receiver 20 by an interlocking lug arrangement 37 and rivets or screws 38, as shown in Fig. 18. Receiver extension 36 supports a buffer housing 39 which contains any conventional energy absorbing means. A buffer plate 41 extends forwardly out of buffer housing 39 against which operating slide 50 strikes, as will be later described.

Bolt 40 comprises a cylindrical body portion 42 terminating in a depending rectangular base portion 43 which slidably engages the ways 35 in receiver 20. An axial hole 44 is provided in the cylindrical portion 42 of bolt 40 to receive a firing pin 45. A substantially vertically disposed recess 46 is provided in the bottom of rectangular portion 43 of bolt 40 for a purpose to be later described. A vertical slot 47 communicates recess 46 with hole 44 and permits a tang 48 provided on the rear of firing pin 45 to project downwardly into recess 46. The forward face of bolt 40 is provided with a cylindrical recess 49 coaxial with hole 44 to receive the head of a cartridge 51, as shown in Fig. 1.

A locking shoulder 52 is provided on bolt 40 near the forward end thereof as shown in Fig. 5 and is produced by a substantially semi-annular groove provided about the periphery of the cylindrical portion 42 of bolt 40. Such groove, however, is eccentrically formed with respect to the axis thereof so that such groove terminates at

approximately the sides of the circular portion of the bolt. The forward face of shoulder 52 is sloped to facilitate unlocking of a breech lock 54, as will be later described.

On the underside of bolt 40 on the forward cylindrical portion thereof, there is provided a slot 53 as shown in Fig. 5. Such slot is longitudinally disposed with respect to the axis of cylindrical portion 42 of bolt 40 and is of suitable width to accommodate an extractor 55. A rectangular recess 56 is provided above and communicating with slot 53 to receive a transverse lug 57 provided on extractor 55. A transverse hole 58 is provided in bolt 40 which intersects recess 56. A pin 60 is insertable in hole 58 and is engageable with a hook portion 59 provided on lug 57 of extractor 55. Such pin thereby pivotally secures extractor 55 within slot 53. A cylindrical recess 61 is provided near the rear end of slot 53 and a corresponding cylindrical recess 62 is provided near the end of extractor 55 to accommodate a spring 63 which is provided to bias the forward end of extractor 55 into engagement with the rim of cartridge 51.

Bolt 40 is reciprocated on ways 35 within receiver 20 by operating slide 50 which is slidably mounted on ways 34 in receiver 20. Operating slide 50 is essentially a rectangular bar and a vertically disposed integral lug 64 is provided at the rear end of such slide as shown in Figs. 15 and 16. Lug 64 rests within recess 46 thereby cooperating with bolt 40 to effect movement of such bolt when the slide is actuated, as will be later described. A transverse slot 65 is provided on top of lug 64 to receive tang 48 of firing pin 45. Thus operating slide 50 acts as a hammer to actuate firing pin 45 to discharge cartridge 51 and also retracts firing pin 45 affording a safety feature, in a manner to be subsequently described.

A longitudinal slot 66 is provided in the center of operating slide 50 as shown in Fig. 16 in order that such slide can surround a bolt lock 54 and to permit assembly of such bolt lock as will be described in greater detail later.

Bolt lock 54 is a substantially rectangular member provided approximately in the center thereof with a hole 67, as shown in Fig. 11, which surrounds the cylindrical portion of bolt 40. Bolt lock 54 is provided with a depending integrally formed lug 68 which is of substantially inverted T-shape construction. The stem of such lug is provided with a longitudinal rectangular recess 69 for a purpose to be later described. Near the bottom of lug 68 there is provided a transverse hole 70, shown in Fig. 10, and a corresponding hole 71 is provided at the juncture of the stem portion of lug 68 and the rectangular portion of lock 54. On the opposite sides of lug 68 there are provided sloped surfaces 72 as shown in Fig. 10 which support a pin 73 inserted through hole 70. A corresponding pin 74 is inserted through the hole 71 for a purpose which will presently appear. The forward face of lock 54 is beveled adjacent hole 67 to cooperate with the sloped locking shoulder 52 provided on bolt 40 whereby the lock cooperates to securely lock bolt 40 to the firearm in a manner to be later described.

To permit the depending lug 68 of lock 54 to be assembled to operating slide 50, a pair of opposed vertically disposed slots 75 are provided near the forward end of slot 66 in slide 50 shown in Fig. 16. Near the rear of slide 50 on the top surface thereof, as shown in Figs. 15 and 16, there is provided a pair of oppositely disposed

cam grooves 76 which are provided on the upper face of operating slide 50 adjacent slot 66 and extending downwardly therein. A pair of oppositely disposed cam grooves 117 are provided on the underside of slide 50 and opposed to cam grooves 76. Thus during counter-recoil when cam grooves 76 of slide 50 reach pin 74 of lock 54, such lock will be forced downwardly into locked relationship with bolt 40. Pin 74 drops into grooves 76 during the downward locking movement of the breech lock and is effected by pin 73 engaging the rear run-out of cam grooves 117. Pin 73 is raised into cam grooves 117 during the upward unlocking movement of the breech lock and is effected by pin 74 engaging the forward run-out of cam grooves 76.

A longitudinally disposed hole 77 is provided on the forward end of slide 50 as shown in Fig. 15 and such hole is counterbored and threaded as shown at 78 to receive a tubular operating rod or piston 79.

With buffer housing 39 removed, slide 50 with bolt 40 thereon is assembled in the receiver as a unit, lug 64 cooperating with recess 46 to effect such connection whereupon slide 50 and bolt 40 are pushed into the battery position as shown in Fig. 1. Prior to moving the bolt and slide into battery position, lock 54 is dropped into a slot 80 which is vertically disposed in receiver 20 whereupon the depending lug 68 on lock 54 is engageable with operating slide 50 as previously described. Thus the cylindrically formed portion 42 of bolt 40 can enter hole 67 in lock 54 so that such bolt may be moved into a locked battery position as will be later described.

In the battery position of bolt 40 and slide 50 a considerable portion of such slide projects forwardly beyond the end of the receiver and such end is maintained within a rectangular housing 81, such housing being connected to the forward end of receiver 20, while the other end of such housing is connected to a coupling member 82 which in turn receives one end of a gas cylinder 83. Such gas cylinder is supported by a front barrel bearing support 84. Operating rod 79 is provided with a piston 85 in one end which slidably cooperates with gas cylinder 83. A gas port 86 is provided in barrel 30 which communicates with cylinder 83 by means of a hole 87 in front barrel bearing support 84 to admit gas to the end of piston 85 whereby slide 50 is actuated.

A spring 88 is contained within the hollow interior of operating rod 79 and one end of such spring surrounds a spring guide 89. Spring 88 abuts a plate member 90 integrally formed or otherwise secured to the end of guide 89 and such plate is in turn releasably secured to receiver 20 by means of a retainer 91 pivotally secured to plate 90 as by a pin 92. One end of retainer 91 is engageable with a notch 93 provided in the bottom of receiver 20 as shown in Fig. 1 whereby operating spring 88 and spring guide 89 are retained within housing 81 and cylinder 83.

In the position shown in Fig. 1, retainer 91 secures such spring and guide rod to the firearm. When, however, a forward force is exerted against retainer 91 to disengage the bottom end of such retainer from the rear shoulder of notch 93, retainer 91 may be pivoted clockwise out of engagement with notch 93 and thus the spring 88 and spring guide 89 may be readily removed from the firearm through the receiver thereof. Assembly of such retainer to the receiver is accomplished by a reversal of the procedure just described, namely, the spring and spring guide and

retainer are pushed forwardly and released when retainer 91 is over notch 93 whereby the rearward bias of spring 88 pivots retainer 91 into notch 93 thereby securing the rear end of the spring and spring guide.

The open construction of slide 50 permits such slide to surround retainer 91 whereby the reciprocating movement of the slide is not interfered with. To insure that bolt 40 goes into locked battery position in properly spaced relationship with slide 50 throughout its entire counter-recoil travel, a latch 94 is provided for such purpose. Latch 94 is pivotally mounted within a suitable vertically disposed slot 95 provided slightly ahead of lug 64. A transverse pin 96 pivotally mounts latch 94 within slot 95. Latch 94 is substantially L-shaped and a spring biased plunger 97 mounted in a hole 98 provided in lug 64 contacts the leg of latch 94 adjacent such plunger to bias the other end of latch 94 upwardly. A latching shoulder 99 is provided on top of latch 94 which engages an integral projecting lug 100 provided on the underside of bolt 40. Thus when latch 94 is in engagement with lug 100, such latch forces the bolt forwardly in spaced relationship to slide 50.

Shoulder 99 of latch 94 is disengaged from lug 100 on bolt 40 when the forward end of such latch enters recess 69 in bolt lock 54. The rearwardly facing entrance of slot 69 is beveled as shown at 101 to permit the forward end of latch 94 to readily enter such slot and cam lock 54 downwardly. Thus slide 50 is disengaged from bolt 40 to move forwardly after such bolt is in the locked breeched position.

Prior to inserting cartridge 51 into the chamber of the firearm by bolt 40, the cartridge is supported by a pair of parallel cartridge supporting rods 103. The forward reduced ends 101 of rods 103 are rotatably mounted in holes 102 of receiver 20 and the buffer housing 39 holds such rods forwardly in position. Bolt 40 is provided with a pair of longitudinally disposed spaced parallel holes 104 to receive rods 103. A longitudinally disposed cam slot 105 is provided in each rod 103 and is disposed along the length of such rod as shown in Fig. 9. A pin 106 secured in each side of bolt 40 is engageable with cam slot 105 in each rod 103, thus as bolt 40 slides along rods 103, pins 106 effect turning of such rods in accordance with a path governed by cam slot 105. A substantial portion of the length of rods 103 is flattened as shown at 107 in Figs. 3 and 4. Hence when such rods are turned to the position shown in Fig. 3, cartridge 51 is retained in feedway 102 as the upper edge of such flattened portion is rotated inwardly thereby closing the gap between such rods and thus providing support for the cartridge.

After the cartridge has been chambered and during the last increment of forward movement of the bolt, rods 103 are rotated in position as shown in Fig. 4. Likewise after ejection is complete, the rods are rotated to the position as shown in Fig. 3 during the last increment of recoil travel.

Actuation of feed slide 29 in cover 25 is effected by feed lever 32. A short lever 108 disposed at a substantial obtuse angle to lever 32 is integrally formed with such lever as shown in Fig. 12. At the extremity of such lever there is provided a U-shaped notch 109 which is engaged by another lever 110. Such lever has a rounded end 111 for uniform contact with notch 109. Lever 110 is secured to a shaft 112. Shaft 112 is rotatably

mounted in a vertically disposed hole 113 provided in receiver 20 adjacent one end of slot 80 therein. A similar hole 114 is provided on the opposite side of slot 80 whereby such shaft may be mounted on the opposite side of the receiver as will be later described. A lever 115 provided with a rounded end 116 is secured to the lever end of shaft 112 and the rounded end 116 thereof engages a cam groove 118 longitudinally disposed on the side of operating slide 50. Groove 118 is so shaped that as the slide moves in its longitudinal path, the lever 115 being in contact with such groove, will effect rotation of shaft 112, in turn rotating lever 110, thence lever 108, thereby effecting pivotal movement of lever 32 which in turn translates such action to transverse movement of slide 29 with respect to the longitudinal axis of the firearm, thus a belt of cartridges may be fed through a feedway 102 of the firearm as operating slide 50 reciprocates within the receiver. By mounting shaft 112 in the opposed vertically disposed hole 114 in receiver 20 and by suitably remounting or reversing lever 32, the firearm can be readily converted to feeding from the side opposite to the one above described. A cam groove 120 identical to groove 118 and opposed thereto is provided in operating slide 50 to effect rotational movement of shaft 112 when feeding from the opposite direction.

Any suitable fire control mechanism may be utilized with this firearm to retain the bolt and operating slide in the recoil position and to effect release thereof when and as desired. A sear 119 is shown in Fig. 7 for retaining bolt 40 in operating slide 50 in the recoil position. Such sear is not shown connected to a fire control mechanism as any such mechanism may be utilized to effect release thereof.

Operation

In the breeched battery position of the breech elements of the firearm, as shown in Fig. 1, bolt lock 54 is in locked relationship with bolt 40, hence the bolt is securely locked to the receiver. In such figure the operating slide 50 is shown in its extreme forward position wherein such slide has carried the firing pin 45 forwardly to discharge cartridge 51. Upon discharge thereof a portion of the bullet propulsion gases escape through gas port 86 into gas cylinder 83 whereupon such gases impinge on the face of piston 85 thus forcing the operating rod 79 rearwardly against the bias of operating spring 88, operating rod 79 being connected to slide 50 forces such slide rearwardly.

As slide 50 moves to the rear approximately $\frac{3}{4}$ ", cam grooves 76 force pin 74 of lock 54 upwardly thereby raising lock 54 out of engagement with bolt 40 whereupon lug 64 of slide 50 contacts and forces bolt 40 rearwardly to the recoil position against buffer plate 41. Driving spring 88 then returns operating slide 50 forwardly carrying bolt 40 along with such slide.

Shoulder 99 of latch 94 engages lug 100 of bolt 40 to maintain bolt 40 ahead of slide 50 or in spaced relationship with such slide in order that bolt 40 can readily pick up cartridge 51 in feedway 102, lever 32 in the meantime has been pivoted by shaft 112 to move slide 29 across the feedway to position the cartridge directly in front of bolt 40 so that such bolt can advance a cartridge into the chamber of firearm barrel 30.

During the counter-recoil movement of the bolt 40 in slide 50, cartridge support rods 103 have been rotated to the position shown in Fig.

4 whereby the flattened portion 107 thereof is vertically disposed so that the empty cartridge case extracted by extractor 55 from barrel 30 can be ejected downwardly through receiver 20. After the bolt has traveled approximately its recoil travel, rods 103 are rotated to the cartridge supporting position shown in Fig. 3 as governed by cam slots 105. As the bolt proceeds into battery position, rods 103 are again rotated by pins 106 being in engagement with cam grooves 105 to the position as shown in Fig. 4. As a cartridge is about to be seated in the chamber of the barrel, latch 94 enters slot 69 of breech lock 54 whereby latch 94 is unlocked from bolt 40 allowing such bolt to move into the locked battery position shown in Fig. 1. When the bolt is in battery position, operating slide 50 proceeds forwardly approximately $\frac{1}{2}$ " to lock the bolt whereupon slide 50 continues forwardly approximately an additional $\frac{1}{4}$ " to drive firing pin 45 against the primer of a cartridge 51 seated in the chamber thereby effecting discharge of such cartridge whereupon the cycle of operation just described is repeated over again.

From the foregoing description it is apparent to those skilled in the art that a firearm of the automatic type having a bolt of comparatively light weight is hereby provided which will readily attain a high rate of fire as the reciprocating members which include the bolt and operating slide have relatively light weight as compared to prior art firearms, hence enabling such elements to be rapidly moved. The firearm herein disclosed is positively and securely locked at the moment of discharge of each cartridge thereby insuring a safe firearm at all times. The cartridge feeding means is positively assured by the cam action of the slide effecting rotation of the belt feed lever thus insuring that timing thereof will be maintained at all times. The feature of supporting the round in the feedway as such round is being chambered is unique as such cartridge support will permit ejection of the empty cartridge through the receiver on the recoil stroke of the firearm.

I claim:

1. In a firearm having a receiver, a bolt slidably mounted in the receiver for longitudinal reciprocating movement between a battery position and a recoil position, said bolt having a semi-annular groove on the upper part thereof, an operating slide connected to said bolt, said slide being mounted in the receiver for reciprocal movement, a bolt lock slidably mounted in the receiver and adapted to surround said bolt in the battery position thereof, and means for engaging or disengaging said lock with said semi-annular groove in timed relationship with respect to the relative position of said slide whereby said bolt is locked or unlocked relative to the receiver.
2. In a firearm having a receiver, a bolt slidably mounted in the receiver for reciprocal movement between a locked breeched position and a recoil position, said bolt having a cylindrical head provided with an annular locking groove thereon, an operating slide connected to said bolt and mounted in the receiver for reciprocal movement, a bolt lock slidably mounted in the receiver for vertical movement, said bolt lock having a hole therethrough arranged to receive the cylindrical head of said bolt in the battery position thereof, cam means on said operating slide, and means on said bolt lock engageable with said cam means on said operating slide whereby said bolt lock is moved into or out of

engagement with said locking groove in timed relationship with respect to the relative position of said slide for locking or unlocking said bolt relative to the receiver.

CLARENCE E. SIMPSON.
